UNITED STATES PATENT OFFICE.

ANDREW PATTERSON, OF BIRMINGHAM, PENNSYLVANIA.

IMPROVEMENT IN MANUFACTURE OF HOES.

Specification forming part of Letters Patent No. 24,658, dated July 5, 1859.

To all whom it may concern:

Be it known that I, ANDREW PATTERSON, of the borough of Birmingham, county of Allegheny, State of Pennsylvania, have invented a certain new and useful Improvement in the Manufacture of Hoes; and I hereby declare that the following is a full and exact description of the same, reference being had to the accompanying drawings, and to the letters of reference marked thereon.

The nature of my invention consists in casting the head or eye of the hoe on or around the blade, which has been previously prepared and placed in a mold so as to properly receive the molten metal of which the head or eye is to be cast, for which purpose ordinary cast-iron is most suitable, but other metals would answer.

The better to enable others to manufacture hoes in accordance with my improvement and to produce my improved manufacture of hoe, I will more fully describe it in detail in view of the drawings, of which—

Figure 1 is a perspective of a finished hoe, or of the pattern used in molding. Fig. 2 is an outline or plan of the same. Fig. 3 is a section through the head or eye and plate. Fig. 4 is an outline or plan of the blade as prepared to receive the molten head or eye. The blade should consist of sheet steel or iron.

The same letters refer to like parts in all the drawings.

a is the blade. *b* is the head or eye. *b'* is the hole through the head to receive the handle. *d d* are jaws or projections which flow from the head on each side of the blade so as to securely clasp it, and also to give stiffness to the blade. *c c c* are holes through the blade to permit the molten metal flowing through and uniting the jaws *d d* into one solid mass. *x* is a cut in the blade corresponding with the eye

or hole for the handle, than which it (*x*) should be somewhat greater in diameter.

In manufacturing my hoe I proceed as follows: Having determined the shape and configuration of hoe which I desire to produce, which may be of any ordinary shape or style, I prepare a pattern of the perfect hoe, and, having molded an impression from it in sand or other suitable material, I place the blade in the mold in its proper position, and, having closed the mold, I pour the molten metal for the head into the mold, and it flows on and around the blade and fills the impressions made by the jaws *d d* on the pattern. Flowing through the holes *c c c*, it firmly attaches itself to the blade and forms a complete hoe.

I desire to say that the shape of the eye, head, or jaws, or the shape or position of the holes *c c c* or the cut *x* in the blade, is not essential, but may all be varied to suit circumstances in the judgment of mechanics.

I am aware that the heads or eyes of hoes have been cast of malleable iron and afterward attached to the blade by welding or riveting. I do not therefore desire to claim such cast hoe-heads.

I do not claim casting hoe-heads, nor casting a flange or projection on such head by which it is attached to the blade; nor do I claim attaching such head to the blade by rivets, as all these have before been used; but

I do claim as my invention—

The combination of the two jaws *d d*, which clasp the blades, with the head *b* and the blade *a*, arranged and constructed substantially as set forth.

A. PATTERSON.
